VAPOR GENERATORS WITH SUPERHEAT TEMPERATURE CONTROL

Edward G. Hutchings, Whitton, Twickenham, England, assignor to The Babcock & Wilcox Company, New York, N. Y., a corporation of New Jersey

Application August 21, 1952, Serial No. 305,602

Claims priority, application Great Britain September 5, 1951

10 Claims. (Cl. 122—477)

This invention relates to tubular vapor generating and superheating units of the kind comprising parallel connected gas passes leading from a combustion chamber and a vapor heater so disposed in relation to the passes that the vapor temperature at the outlet from the heater may be controlled by regulation of the distribution of the heating gas flow between the passes. In such a unit there may be, for example, two parallel passes generally with the whole superheater disposed in one of the passes, although the superheater may be arranged with substantially the whole thereof disposed in one pass and the remainder thereof disposed in the other pass. In a marine steam boiler, for instance, normally a high steam temperature is required, so that the dampers of the pass in parallel with the superheater pass are nearly closed. On the other hand, when maneuvering, a low steam temperature is required, so that the dampers of the superheater pass are nearly closed. In both cases, therefore, a resistance to gas flow is set up by the dampers. An object of the invention is the provision of improved means for controlling the distribution of gas flow between the parallel gas passes of a tubular vapor generating and superheating unit.

The present invention includes a tubular vapor generating and superheating unit comprising parallel connected gas passes leading from a combustion chamber and a vapor heater so disposed in relation to the passes that the vapor temperature at the outlet from the heater may be controlled by regulation of the distribution of the heating gas flow between the passes, together with control means arranged differentially to vary flow areas of gas paths respectively in series with the said passes and containing heat exchange means, and thereby to regulate the distribution of gas flow between the passes while minimizing unbalance of draft loss between said parallel passes and difference in gas outlet temperatures from the continuations of said passes over portions of said heat exchanger.

The invention also includes a tubular vapor generating and superheating unit comprising inclined vapor generating tube banks at opposite sides of a combustion chamber and extending between lower lateral liquid drums and a central upper vapor and liquid drum, the drums having their axes parallel to one another, respective tube screens between the banks and the combustion chamber, and a superheater between one of the tube screens and the corresponding bank, a boiler casing providing passages adapted to lead the gases flowing from the respective tube banks to respective spaces above the front and rear parts of the vapor and liquid drum, an economizer in a gas uptake above said spaces, baffles transverse to the axis of the vapor and liquid drum subdividing the gas flow past economizer surfaces into separate gas passages, and a swinging damper adapted selectively to determine whether a passage between adjacent baffles shall receive gas from the one or from the other of the said spaces.

The invention will now be described, by way of ex-

2

ample, with reference to the accompanying drawings, in which:

Fig. 1 illustrates a scheme of gas flows past heat exchange surfaces, including vapor heating surfaces, of a vapor generating and superheating unit having control means for differentially varying the flow areas of certain heating gas paths, and

Figs. 2 to 4 show elements of a water tube marine boiler, Fig. 2 being a front elevation thereof in section on the lines 2—2 of Figs. 3 and 4, Fig. 3 being an outside view from the left of the upper part of the boiler, as indicated by the line 3—3 of Fig. 2, part of the casing being shown broken away, and Fig. 4 being a side view from the left of the upper part of the boiler in section on the line 4—4 of Fig. 2.

In Fig. 1 of the drawings elements of a vapor generating and superheating unit are indicated; combustion gases are shown as flowing from a combustion chamber 1 to deliver heat to heat exchange surfaces disposed in two gas passes 2 and 3 arranged for the flow of combustion gases in parallel therethrough and then to deliver heat to an economizer 4 in a subsequent gas pass 5 connected to suitable draft producing means, such as an induced draft fan (not shown). The heat exchange surfaces in the first parallel pass 2 consist of a vapor generating screen section 6 and, in the gas flow path behind the screen section, a vapor generating section 7, and the heat exchange surfaces in the second parallel pass 3 consist of a vapor generating screen section 8, a superheater 9 in the gas flow path behind the screen section 8, and a vapor generating section 10 in the gas flow path behind the superheater 9. The gases from the first and second parallel passes 2 and 3 are led to respective spaces 11 and 12 in front, as regards the direction of gas flow, of the economizer 4 and on opposite sides of a swinging damper 13, which can be moved to one side or other of a neutral position so as to restrict to a greater or lesser extent the gas flow into the economizer 4 from either the space 11 or the space 12.

In the gas pass 5 a number of baffles 14—18 are provided which extend through the economizer 4, and extend parallel to opposite walls 19 and 20 of the gas pass 5 and to the axis of the damper 13 and subdivide the gas pass 5 into a number of separate passages 21—26.

The damper 13 and the baffles 14—18 are so arranged that the damper can determine by its position whether any of the passages 22—25, lying between the two outermost passages 21 and 26, which latter are respectively adjacent the gas pass walls 19 and 20, is included in the gas path from the space 11 or the gas path from the space 12. As shown, the edge of the damper remote from its axis is adjacent the baffle 15, and a gas path consisting of the passages 21 and 22 arranged in parallel is placed in series with the gas pass 2 containing the screen section 6 and vapor generating section 7, and a gas path consisting of the passages 23—26 arranged in parallel is placed in series with the gas pass 3 containing the screen section 8, superheater 9 and vapor generating section 10.

The relative quantities of gases flowing in the gas passes 2 and 3 depend upon the respective flow areas of the paths consisting of the passages 21 and 22 and of the passages 23—26. A second damper 27, which in its open position lies against the wall 20 but which closes towards the damper 13, is provided for independently varying the relative gas quantities flowing through the passes 2 and 3.

In the operation of the unit, by varying the position of the damper 13 so that the gas passage previously in one gas path in the pass 5 is instead included in the other gas path in the pass 5 and adjusting so far as necessary the firing rate of the combustion chamber so that the same quantity of vapor is produced by the unit at

the same pressure, the superheat temperature at a given load can be varied; alternatively, by appropriately varying the position of the damper 13 as the load changes, the superheat temperature can be regulated over a range of loads. If a superheat temperature is required which is between that obtained with the damper edge positioned adjacent one baffle and that obtained with the damper edge positioned adjacent the next baffle, then the damper may be set to that of the two positions yielding the higher superheat temperature and the gas flow through the gas path 3 including the superheater 9 is reduced by operating the second damper 27 to a suitable extent from the open towards the closing position.

The arrangement provides a simple method of superheat control. It will be observed, moreover, that the turning of the damper 13 to a position in which it is effective to reduce the flow area in the gas pass 5 for the gases from one of the gas passes 2 and 3 is simultaneously effective to increase the flow area in the gas pass 5 for the gases from the other of the two gas passes 2 and 3; it follows that the gas flow resistance of the unit as a whole is not so greatly increased as otherwise, and hence the available draft or fan power is used more effectively; and that those gases in the gas path of which the flow area is increased are caused to contact more economizer surface and hence leave the unit with less heat than otherwise would be the case; in other words the boiler efficiency is increased. Dampers 13 and 27 are arranged so that they may be brought to positions in which they together prevent the flow of gases in the pass 3 in which the superheater 9 is arranged. If they are brought to such positions for the starting up of the unit, the starting up may be hastened without the risk of damaging the superheater, which has initially no steam flow therethrough.

Figs. 2-4 are views of a water tube marine boiler having a steam and water drum 50 extending from the front to rear above a combustion chamber 51 arranged to be fired through its front wall by oil burners 52. A water drum 53 below the drum 50 and to the right of the combustion chamber 51 is connected with the drum 50 by an inwardly and upwardly inclined bank 54 of vapor generating tubes, and a water drum 55 below the drum 50 and to the left of the combustion chamber 51 is connected to the drum 50 by an inwardly and upwardly inclined bank 56 of vapor generating tubes. On the combustion chamber side of the bank 54 are three rows of screening tubes 57. On the combustion chamber side of the bank 56 are three rows of screening tubes 58, and between the rows of screening tubes 58 and the bank 56 is a bank of superheater tubes 59.

Above the drum 50 is a gas uptake 60 in which is arranged an economizer 61. The casing 62 on the right-hand side of the boiler is designed so as to lead gases flowing upwardly and outwardly through the rows of screening tubes 57 and the bank 54 to a space 63 above the bank 54, upwardly from this space 63 past the level of the center of the drum and forwardly and then inwardly to a space 64 above the drum and below the front part of the economizer. The boiler casing 62 on the left-hand side of the boiler is designed so as to lead gases flowing upwardly and outwardly through the rows of screening tubes 58, the superheater 59, and the bank 56 to a space 65 above the bank 56, upwardly from this space 65 past the level of the center of the drum 50 and rearwardly and then inwardly to a space 66 above the drum and below the rear part of the economizer. Insulation 67 extending around the front upper right-hand quadrant of the drum and from the top of the front part of the drum to a downward extension 68 of the left-hand wall 69 of the gas uptake 60 forms the bottom of the space 64, and insulation 70 extending around the rear upper left-hand quadrant of the drum and from the top of the rear part of the drum to a downward extension 71 of the right-hand wall 72 of the gas uptake 60

forms the bottom of the space 66. The insulation 67 extends rearwardly and insulation 70 extends forwardly to a vertical plate 73 whose lower edge embraces the upper semi-circle of the drum and whose upper edge is horizontal a short distance above the insulations 67 and 70.

Between the spaces 64 and 66 there is pivoted on a horizontal axis at its lower edge 80, which is transverse to the axis of the drum 50, a swinging damper 81, which 10 has suitably secured at one end of its operating spindle a counter-weight 82 and at the other end thereof operating means 83, and is adapted to be turned between a position in which it extends forwardly and upwardly at an angle of 45 degrees, through a neutral position in 15 which it extends vertically upwardly, to a position in which it extends upwardly and rearwardly at an angle of 45 degrees.

The economizer 61 comprises tube lengths extending parallel to the axis of the drum 50 and arranged in horizontal rows and in fourteen vertical rows. The group 84 of the lower seven rows is spaced from the group 85 of the upper seven rows. The gas flow upwardly through the lower group of economizer tube rows is subdivided by thirteen vertical baffles 86 extending transversely of 20 the economizer tubes into fourteen gas passages 99. Downward extensions 86' of the baffles 86 are provided of such lengths that their ends lie closely adjacent the arc of swing of the upper edge of the damper 81; the five front baffle extensions 86' are sloped rearwardly and the five rear baffle extensions 86' are sloped forwardly towards the vertical through the axis of the baffle 81.

The gas flow through the upper group of economizer tube rows is subdivided by fourteen baffles 115 extending transversely of the economizer tubes into fifteen gas passages 129.

The baffles 115 are staggered with regard to the baffles 86 and in the space between the lower economizer tube group 84 and the upper economizer tube group 85 is disposed a series of thirteen pivoted dampers 145 having 30 their axes of rotation adjacent the upper edges of the baffles 86, and each arranged so that its upper edge can be brought adjacent to the lower edge of one or adjacent the lower edge of the other of those two of the baffles 115 lying closest to the vertical plane through the axis of the 35 baffle of the lower series 86 to which the damper is adjacent. Operating means 158 are provided for moving simultaneously all the dampers 145 from one of the said positions to the other.

When the damper 81 is moved from a position in which 40 the upper edge is adjacent to one of the baffle extensions 86' to a position in which its upper edge is adjacent another of the baffle extensions 86', the flow areas of the two gas paths, each consisting of one or more of the 45 passages 99, through the lower group 84 of economizer tube rows, which gas paths are respectively in series with the gas passes through the screening tubes 57 and vapor generating tube bank 54, and through the screening tubes 58, superheater 59, and vapor generating tube bank 56, are differentially varied to control the degree of superheat, 50 in the manner described in connection with the operation of the damper 13 with reference to Fig. 1. The relatively large number of the baffles 86 provides a relatively fine control of superheat although the damper 81 may not be moved to positions so that its upper edge is between two 55 of the baffle extensions. The fineness of superheat control is increased by the provision of the dampers 145 controlling the gas flows to the passages 129 between the baffles 115 in the upper group of economizer tube rows; thus the dampers 145 can act to extend the baffles 86 60 either respectively to the baffles 115, or, if the dampers are moved to their other extreme positions, respectively to the baffles 115, and thus for each possible distribution of the total gas flow through the passages 99 there corresponds two possible distributions of the total gas flow to the 65 passages 129. As shown in Fig. 4 the upper edge of the 70

damper 81 is adjacent the extension 86' of the fourth baffle 86 and the dampers 145 extend the baffles 86 to the respective baffles 115 at the front thereof.

The present invention thus provides a vapor generating and superheating unit in which the superheated vapor temperature can be closely regulated by varying the amount of the heating gases passing over the superheating surface, while a high overall thermal efficiency for the unit is maintained by the use of auxiliary heat absorbing surface and control of the heating gas flow over said auxiliary surface to effect a minimum unbalance of the draft loss and gas outlet temperature between a gas flow path containing the superheating surface, vapor generating surface, and a portion of the auxiliary surface and a second gas flow path containing vapor generating surface and the remaining portion of the auxiliary surface.

While in accordance with the provisions of the statutes I have illustrated and described herein the best form of the invention now known to me, those skilled in the art will understand that changes may be made in the form of the apparatus disclosed without departing from the spirit of the invention covered by my claims, and that certain features of the invention may sometimes be used to advantage without a corresponding use of other features.

I claim:

1. A tubular vapor generating and superheating unit comprising a combustion chamber, a pair of parallel gas passes opening to said combustion chamber, a vapor superheater having its heat absorbing surface positioned in one of said gas passes so that the vapor temperature at the outlet from said superheater may be controlled by regulation of the distribution of the gas flow between said gas passes, a plurality of heating gas passages in series with said gas passes, an auxiliary heat exchanger in said heating gas passages, and control damper means at the heating gas inlet side of said heating gas passages movable differentially to vary the effective flow areas of said heating gas passages respectively and thereby to regulate the distribution of gas flow between said gas passes.

2. A tubular vapor generating and superheating unit comprising a combustion chamber, vapor generating tube banks at opposite sides of said combustion chamber, a group of vapor superheating tubes arranged adjacent one of said tube banks, a casing for said unit arranged to provide a gas uptake and gas passes adapted to lead the heating gases flowing from the respective tube banks to said gas uptake, an auxiliary heat exchanger in said gas uptake, a series of baffles arranged to subdivide the heating gas flow over said heat exchanger into separate heating gas passages, and a swinging damper movable to selectively determine whether a heating gas passage between adjacent baffles shall receive gas from one or the other of the said gas passes.

3. A tubular vapor generating and superheating unit comprising a combustion chamber, oppositely inclined vapor generating tube banks at opposite sides of said combustion chamber, a central upper vapor and liquid drum and a pair of lower laterally spaced liquid drums connected to corresponding tube banks, a group of vapor superheating tubes arranged adjacent one of said tube banks, a casing for said unit arranged to provide passages adapted to lead the heating gases flowing from the respective tube banks to respective spaces above the vapor and liquid drum, an economizer in a gas uptake above said spaces, a series of baffles arranged to subdivide the gas flow over said economizer into separate gas passages, and a swinging damper movable to selectively determine whether a gas passage between adjacent baffles shall receive gas from one or the other of the said spaces.

4. A tubular vapor generating and superheating unit comprising a combustion chamber, oppositely inclined vapor generating tube banks at opposite sides of said combustion chamber, a central upper horizontally elongated vapor and liquid drum and a pair of lower laterally spaced liquid drums connected to corresponding tube

banks, said drums having their longitudinal axes substantially parallel to one another, a group of vapor superheating tubes arranged adjacent one of said tube banks, a casing for said unit arranged to provide passages adapted to lead the heating gases flowing from the respective tube banks to respective spaces above the front and rear parts of the vapor and liquid drum, an economizer in a gas uptake above said spaces, a series of baffles extending transversely of the longitudinal axis of the vapor and liquid drum and arranged to subdivide the gas flow over said economizer into separate gas passages, and a swinging damper movable to selectively determine whether a gas passage between adjacent baffles shall receive gas from one or the other of the said spaces.

5. A tubular vapor generating and superheating unit comprising a combustion chamber, oppositely inclined vapor generating tube banks at opposite sides of said combustion chamber, a central upper vapor and liquid drum and a pair of lower laterally spaced liquid drums connected to corresponding tube banks, a group of vapor superheating tubes arranged adjacent one of said tube banks, a casing for said unit arranged to provide passages adapted to lead the heating gases flowing from the respective tube banks to respective spaces above the vapor and liquid drum, an economizer in a gas uptake above said spaces, a series of baffles arranged to subdivide the gas flow over said economizer into separate gas passages, and a swinging damper movable to selectively determine whether a gas passage between adjacent baffles shall receive gas from one or the other of the said spaces, said baffles having their ends adjacent said damper terminating in an arc of a circle having its center on the axis of rotation of said swinging damper.

6. A tubular vapor generating and superheating unit comprising a combustion chamber, oppositely inclined vapor generating tube banks at opposite sides of said combustion chamber, a central upper vapor and liquid drum and a pair of lower laterally spaced liquid drums connected to corresponding tube banks, a group of vapor superheating tubes arranged adjacent one of said tube banks, a casing for said unit arranged to provide passages adapted to lead the heating gases flowing from the respective tube banks to respective spaces above the vapor and liquid drum, an economizer in a gas uptake above said spaces, a series of baffles arranged to subdivide the gas flow over said economizer into separate gas passages, and a swinging damper movable to selectively determine whether a gas passage between adjacent baffles shall receive gas from one or the other of the said spaces, said baffles having their ends adjacent said damper terminating in an arc of a circle having its center on the axis of rotation of said swinging damper and the baffle ends adjacent the damper remote from the plane of the neutral position of said damper being inclined towards the damper axis.

7. A tubular vapor generating and superheating unit comprising a combustion chamber, vapor generating tube banks separately receiving heating gases from said combustion chamber, a group of vapor superheating tubes arranged adjacent one of said tube banks, a casing for said unit arranged to provide a heating gas uptake and passages adapted to lead the heating gases flowing from the respective tube banks to said gas uptake, an economizer in said gas uptake, a series of baffles arranged to subdivide the gas flow over said economizer into separate gas passages, a swinging damper movable to selectively determine whether a gas passage between adjacent baffles shall receive gas from one or the other of the said gas passes, and supplementary damper means arranged to co-operate with said swinging damper to complete the closure of the gas pass containing said vapor superheating tubes.

8. A tubular vapor generating and superheating unit comprising a combustion chamber, oppositely inclined vapor generating tube banks at opposite sides of said combustion chamber, a central upper horizontally elongated

gated vapor and liquid drum and a pair of lower laterally spaced liquid drums connected to corresponding tube banks, said drums having their longitudinal axes substantially parallel to one another, a group of vapor superheating tubes arranged adjacent one of said tube banks, a casing for said unit arranged to provide passages adapted to lead the heating gases flowing from the respective tube banks to respective spaces above the front and rear parts of the vapor and liquid drum, an auxiliary heat exchanger in a gas uptake above said spaces, a series of baffles extending transversely of the longitudinal axis of the vapor and liquid drum and arranged to subdivide the gas flow over said heat exchanger into separate gas passages, and a swinging damper movable to selectively determine whether a gas passage between adjacent baffles shall receive gas from one or the other of the said spaces.

9. A tubular vapor generating and superheating unit comprising a combustion chamber, oppositely inclined vapor generating tube banks at opposite sides of said combustion chamber, a central upper horizontally elongated vapor and liquid drum and a pair of lower laterally spaced liquid drums connected to corresponding tube banks, said drums having their longitudinal axes substantially parallel to one another, a group of vapor superheating tubes arranged adjacent one of said tube banks, a casing for said unit arranged to provide passages adapted to lead the heating gases flowing from the respective tube banks to respective spaces above the vapor and liquid drum, an auxiliary heat exchanger in a gas uptake above said spaces having upper and lower sections, a series of baffles extending transversely of the longitudinal axis of the vapor and liquid drum and arranged to subdivide the gas flow over said heat exchanger lower section into separate gas passages, a swinging damper movable to selectively determine whether a gas passage between adjacent baffles shall receive gas from one or the other of the said spaces, a second series of baffles extending transversely of the longitudinal axis of the vapor and liquid drum and arranged to subdivide the gas flow over said heat exchanger upper section into separate gas passages, and a series of swinging dampers positioned between said economizer upper and lower sections and movable to act as extensions of the first series of baffles either to one or another set of said second series of baffles.

10. A tubular vapor generating and superheating unit comprising a combustion chamber, oppositely inclined vapor generating tube banks at opposite sides of said combustion chamber, a central upper horizontally elongated vapor and liquid drum and a pair of lower laterally spaced liquid drums connected to corresponding tube banks, said drums having their longitudinal axes substantially parallel to one another, a group of vapor superheating tubes arranged adjacent one of said tube banks, 5 a casing for said unit arranged to provide passages adapted to lead the heating gases flowing from the respective tube banks to respective spaces above the front and rear parts of the vapor and liquid drum, an economizer in a gas uptake above said spaces having upper and lower sections, 10 a series of baffles extending transversely of the longitudinal axis of the vapor and liquid drum and arranged to subdivide the gas flow over said economizer lower section into separate gas passages, a swinging damper movable to selectively determine whether a gas passage between adjacent baffles shall receive gas from one or the other of the said spaces, a second series of baffles extending transversely of the longitudinal axis of the vapor and liquid drum and arranged to subdivide the gas flow over said economizer upper section into separate gas 15 passages, 20 said second series of baffles being staggered relative to the first series of baffles, a series of swinging dampers positioned between said economizer upper and lower sections and movable to act as extensions of the first series of baffles either to one or another set of said second series of baffles, and means for simultaneously operating said series of swinging dampers.
